UNITED STATES PATENT OFFICE.

IRA BOYD HUMPHREYS, OF DENVER, COLORADO.

ROTARY EXPLOSION-ENGINE.

1,003,263.

Specification of Letters Patent. Patented Sept. 12, 1911.

Application filed January 7, 1911. Serial No. 601,464.

To all whom it may concern:

Be it known that I, IRA BOYD HUMPHREYS, a citizen of the United States, residing at Denver, in the county of Denver and State 5 of Colorado, have invented certain new and useful Improvements in Rotary Explosion-Engines, of which the following is a specification, reference being had therein to the accompanying drawing.

10 My invention relates to improvements in rotary explosion engines, the primary object of which is to provide an improved construction in which the explosive charge is drawn therein, compressed and exploded 15 as the driving element or piston is revolved.

Another object of the present invention is to provide a rotary explosion engine of the compression type, which comprises a rotating piston and two abutments, which rotate 20 in the same direction as the piston, whereby an explosive charge is drawn within the cylinder compressed, exploded and exhausted.

In the accompanying drawings—Figure 1 25 is a sectional view of one form of my improved rotary explosion engine. Figs. 2, 3 and 4 are sectional views showing the positions of the piston and rotary abutments when transferring the compressed charge 30 from the compression chamber to the explosion chamber. Fig. 5 is a sectional view showing the positions of the piston and rotary abutments while the expansion of the ignited gas is acting upon the piston. Fig. 35 6 is a view of a semi-rigid or spring connection from the abutments to the gears which drive them. Fig. 7 shows a way of packing the rotary abutment which does not require a flexible connection between the 40 rotary abutment and the gears.

Referring now particularly to Fig. 1—the cylinder 1 is of approximately circular form and has communicating therewith a sub or auxiliary cylinder 2 of approximately circular form and a sub or auxiliary cylinder 3, communicating with the main cylinder 1, and diametrically opposite the cylinder 2. Revolvably placed within the main cylinder 1 is a piston 4, which is approximately oval in cross-section. Revolvably located in the cylinder 2 is a revoluble abutment 5, approximately of the same cross-sectional shape as the piston 4, and revolvably located in the cylinder 3, is a revoluble abutment 6 of the same cross-sectional shape as the revoluble abutment 5. The shaft 7, of the

piston 4 has fast thereon a gear 8; the shaft 9 of the abutment 5 has secured thereto a gear 10 and the shaft 11, of the abutment 6 has secured thereto a gear 12. Located 60 between and meshing with the gears 8 and 10 is an idler gear 14, and located between the gears 8 and 12 is an idler gear 15. All of these gears are situated outside of the cylinders and they are of the same diameter. 65 By reason of the idler gears 14 and 15, the piston 4 and the revoluble abutments 5 and 6, all rotate in the same direction. The piston 4 is of such length that the packed ends 16 and 17 tightly engage the inner surfaces of the curved wall of the cylinder 1, and the revoluble abutments 5 and 6 are made of such a length that their packed ends 18, 19 and 21 tightly engage the inner surfaces of the cylinders 2 and 3. The revoluble abutments 5 and 6 are of the same length and, consequently, the interior areas of the cylinders 2 and 3 are identical. 70 75

An intake port 22 communicates with the main cylinder 1 at its junction with and at 80 one side of the cylinder 3, and exhaust ports 23 are located at the other side of the cylinder 3.

With the ports in the position shown in Fig. 1, the space 24 at one side of the piston 4 and between its end 25 and the adjacent side of the revoluble abutment 5, constitutes a compression chamber; while the space 26 between the opposite side of the end 25 of the piston and the adjacent end of the revoluble abutment 6 constitutes an intake 85 chamber and the space 27 between the end 28 of the piston 4 (at the opposite side of the piston from the space 24) and the abutment 6, constitutes an exhaust chamber, 90 while the space 29 between the opposite side of the end 28 of the piston 4 and abutment 5 constitutes an explosion chamber. 95

Fig. 6 shows a spring connection between the rotary abutments 5—6, and the gears 10 and 12 which drive them, constructed as follows: The ring 31 is keyed to the shafts 9 and 11, shafts 9 and 11 being keyed to the rotary abutments 5—6. This ring 31 has two lugs 33 diametrically opposite each other. The gears 10 and 12 are not rigid to shafts 9 and 11. The gears 9 and 11 are fitted with two lugs 32 in such position as to limit the turning of the lugs 33; hence ring 31 has a play of about three degrees. 105 The pins 34 are attached to lugs 32 through holes in lugs 33. These pins hold in place 110

springs 36, the tension of which is regulated by the nuts 35. This flexible connection is for the purpose of holding the sides X—X of the tips of the rotary abutments in contact with the surface *a* of the piston 4 while the contact is between the packed end 16 of the piston and the points *y*—*y*, and between end 17 and points *y*'—*y*'.

While the contact is between the points 10 *y*'—*y*', the packing in the ends 18—19—20—21 of the rotary abutments 5—6 keeps the joint tight. While the piston and the rotary abutments are in the position shown in Fig. 1 (and running to the left as shown 15 by arrow) the rotary abutments are held back against the spring 36 (against the direction of rotation) by contact with the surface *a*. When the contact occurs past the point *y*, and up to the position shown in Fig. 20 2, the rotary abutments are forced (by contact with *a*) against the springs 36 and in the direction of rotation. This flexible connection is one way of keeping the contact point tight. This can also be accomplished 25 with the gear held rigid to the rotary abutment shaft, by packing the entire point as in Fig. 7.

The operation of the construction above described is as follows: An explosive mixture has been previously drawn into the chamber 24 by the end 28 of the piston 4, while it was passing through the said space. With the parts shown in the positions in 30 Fig. 1, the explosive charge in the space 24 is being compressed between the end 25 and the piston and the revolute abutment 5. The previously compressed charge is being exploded in the explosion chamber 29 and the previously exploded charge is being exhausted from the chamber 27. As the piston 35 revolves in the direction indicated by arrow, the abutments 5 and 6 are revolved in the same direction as is also indicated by arrows, and the packed end 19 of the abutment 5 remains in contact with the surface *a* of the piston until the said packed end 19 and the end 25 of the piston meet, as shown in Fig. 40 2, at which time the compressed gas is transferred into the space 29' of the cylinder 2. After the packed ends 19 and 16 have 45 passed, then the packed end 16 of the piston 4 is in engagement with the lower surface of the revolving abutment 5 (Fig. 3) until the packed end 16 of the piston and the packed end 18 of the abutment 5 have passed 50 each other (Fig. 4), at which time the compressed gas is transferred to the explosion chamber 29. As soon as the packed end 16 of the piston has passed the ignition plug 55 30, the compressed charge is ignited, and it expands and drives the piston 4 in the direction indicated by arrow. This expansion occurs between the end 25 of the piston and the abutment 5 (Fig. 5).

60 65 The abutment 6 separates the intake port

22, and also the intake chamber from the exhaust chamber 27, and the abutment 5, together with the piston separates the transfer chamber 29' and the explosion chamber 29 from the compression chamber 24.

Having thus described my invention, 70 what I claim and desire to secure by Letters Patent is:

1. An explosion engine of the compression type, comprising a main cylinder, two auxiliary cylinders in communication therewith, an oval-shaped revolute piston in the main cylinder and of a length fitting the internal diameter of the cylinder, a revolute abutment in each auxiliary cylinder, the abutments being oval-shaped and of a length fitting the cylinders, means for revolving the abutments and the piston in the same direction, the shape of the piston being such and the location of the abutments such that the ends of the abutments engage the sides of the piston and the ends of the piston engage the sides of the abutments as the parts are revolved, an intake port at one side of one of the auxiliary cylinders and an exhaust port at the other side, and ignition means located adjacent the other auxiliary cylinder and between it and the exhaust ports.

2. A rotary explosion engine of the compression type, comprising a cylinder having auxiliary cylinders in communication therewith and located diametrically opposite each other, intake and exhaust ports located at opposite sides of one of the auxiliary cylinders, an oval-shaped piston in the main cylinder and of a length to have its ends engage the inner wall of the cylinder, a compression and explosive controlling revolute abutment in one of the auxiliary cylinders, a revolute abutment in the other auxiliary cylinder, said revolute abutments oval-shaped and of a length to have their ends engage the interior surfaces of their cylinders, a rigid gear wheel on the axes of the piston, gear wheels on the axes of the abutments, idler gear wheels between said gears and operatively connecting them, the driving and driven gears of the same diameter, and ignition means between the compression and explosive controlling abutment and the exhaust port, the parts operating substantially as described.

3. A rotary explosion engine of the compression type, comprising a cylinder, a revolute piston therein, revolute abutments co-operating with the piston, intake and exhaust ports, means for revolving the piston and the abutments in the same direction, and an ignition device.

4. A rotary explosion engine of the compression type, comprising a cylinder, a revolute piston therein, revolute abutments co-operating with the piston, intake and exhaust ports, a tension device acting to hold

the engaging surfaces of the abutments and the piston in contact, and an ignition device.

- 5 5. A rotary explosion engine of the compression type, comprising a main cylinder, auxiliary cylinders in communication therewith, oval-shaped revoluble piston in the main cylinder, oval-shaped revoluble abutments in the auxiliary cylinders and coöperating with the piston substantially as described, driving means between the piston and abutments, said driving means having a yielding movement independent of the abutments for the purpose described.
- 10 10. A rotary engine of the compression

type, comprising a main cylinder auxiliary cylinders in communication therewith, a revoluble piston in the main cylinder, revoluble abutments in the auxiliary cylinders and coöperating with the piston, substantially as 20 described, meshing gears operatively connecting the piston and abutments, the abutment gears having spring connections with the abutments for the purpose described.

In testimony whereof I hereunto affix my 25 signature in the presence of two witnesses.

IRA BOYD HUMPHREYS.
